UNITED STATES PATENT OFFICE.

THOMAS TROUGHTON JACKSON, OF BROADBOTTOM, NEAR MANCHESTER, ENGLAND.

LOOM FOR WEAVING.

1,316,159.

Specification of Letters Patent. Patented Sept. 16, 1919.

Application filed December 24, 1917. Serial No. 208,696.

To all whom it may concern:

Be it known that I, THOMAS TROUGHTON JACKSON, subject of the King of Great Britain and Ireland, and resident of Broadbottom, near Manchester, in the county of Lancaster, England, have invented certain Improvements in Looms for Weaving, of which the following is a specification.

This invention relates to improvements in looms for weaving and while particularly applicable to that type of loom for weaving tapes and like small wares wherein one tape or ribbon only is woven at a time, such improvements are applicable to looms in general weaving the wider classes of single fabrics or a plurality of narrow fabrics side by side.

The invention has particular reference to the previously proposed type of loom in which the reed, shuttle race, shuttle boxes and the usual mechanism which reciprocates in an ordinary type of loom are stationary while the warp threads and cloth, healds or heddles and the rollers supporting the yarn and cloth at the back and front of the loom respectively, are reciprocated to enable the weft to be beaten-up by bringing it into contact with the stationary reed.

In the aforesaid type of loom my invention comprises a reciprocating frame supporting the warp yarn and cloth and heald frames, said frame being moved backward and forward in the arc of a circle; pivoted levers or frames are provided for supporting the reciprocating frame and if desired carrying the take-up motion, cloth roller and attendant parts; a warp stop motion is also carried by the pivoted levers or frame and heald-operating mechanism is arranged in a stationary position with relation to the loom frame but connected directly to the heald or heddle frames in such a way as not to interfere with the backward and forward motion of the reciprocating frame.

The object of the foregoing arrangement of parts is to attain a perfect balance of the movable portions of the mechanism and so enable high speeds to be attained with a minimum of power vibration and stress on the working parts; to minimize all strain on the warp and weft threads and to reduce cost of production.

My invention will be fully described with

reference to the accompanying drawings in which:

Figure 1, is a side elevation of a loom constructed in accordance with my invention, Fig. 2, plan of same and Fig. 3, front elevation of same.

With the aforesaid objects in view I arrange to reciprocate the warp threads *a* and cloth *b* toward and from the stationary reed *c* as in the known type of loom and to this end I employ a reciprocable frame *d* supported on the main frame *a'* of the loom or adapted to be slung from above so as to move in the arc of a circle and to enable an equal tension on the warp to be obtained throughout the full stroke of the frame. This frame *d* may be actuated in any suitable way to effect the movement referred to and to work in unison with the picking mechanism which may be of any suitable type. In an embodied arrangement the reciprocable frame *d* is adapted to support the warp *a* at one end, as by a bar or rail *e*, and the cloth *b* at the other, as it is woven, by a bar or roller *f*, the warp passing from a beam or other source outside the loom over rods *g* or rollers and separated from the frame *d* or being arranged to be carried by it and to be affected by its movements, while the cloth *b* passes to the take-up mechanism over bar *f* which mechanism may be arranged separate from or be affected by the movement of the frame.

Where the let-off and warp holding means and the cloth rollers and take-up mechanism move in consonance with the frame *d*, as is preferred, they act as balancing means for the latter to enable a high speed of the frame to be attained, though separate balancing means may be otherwise employed. In the embodied arrangement referred to only the cloth rollers and take-up mechanism are articulated to the moving frame. In other words it is carried on the short arms *h* of doubled-armed levers pivoted at *i* to the main frame *a'*. The long arms *j* of the levers are coupled to the warp and cloth-supporting frame at *f*.

The take-up motion, indicated by way of example in the drawings, comprises a roller *m* journaled in the lever arms *h* and on the same center is a ratchet wheel or free wheel clutch *n* of the ball type which as the lever arms *h* and *s* reciprocate about their cen-

ters, rotate the roller m as required to take-up or feed forward the cloth. The latter holds the parts in position on the return stroke. The movements of the clutch n are effected through rod s'' coupled to one of the levers s''' connected to the clutch. The cloth passes under rod i , around roller m and over another roller p on which it may be wound or preferably pass to other winding means in the direction shown. Roller p is mounted in the free ends of links q pivoted at r to the arms h , the roller being kept in contact with roller m by springs or weights or by screws m' passed through the lower ends of levers h . The levers h may be enlarged at their lower ends to form balance weights m'' if required, in conjunction with the take-up mechanism.

The opposite end of the frame is supported by the other double-armed levers s pivoted at t and counter-balanced at their lower ends by weights s' , the warp passing over the rods or rollers g from a suitable source of supply as already indicated.

The frame d is reciprocated in the arc of a circle by suitable means. In the drawings I have shown it actuated from the main driving shaft u driven by pulley v , a wheel w on said shaft gearing with a pinion x on a stud y , such pinion forming part of or being secured to a balanced crank z which, in turn, is coupled to one end of a link 2 . The other end of said link is coupled to an arm 3 forming part of one of the pivoted arms or levers s . It will be understood that this mechanism is adapted to give a rapid reciprocating motion to the frame d in the arc of a circle in order to bring the fell of the cloth against the reed c which is stationary and fixed to the main frame a^1 of the loom. In this way the beating-up of the weft is accomplished after it is picked through the shed by the shuttle 5 which itself is of usual construction and reciprocated in the well known way on the shuttle race 6 . The shedding of the warp is accomplished by two separate heald frames 7 each vertically-reciprocated upon a separate guide 8 secured to the reciprocating frame d , both the heald frames being separately actuated from the driving shaft u of the loom by means of connecting rods 9 coupled to crank pins 10 on the driving pulley v and disk 17 .

The warp stop mechanism of the loom may be separate from the reciprocating frame d or may be arranged to assist in balancing. In the arrangement shown in the drawings I employ the usual sheet steel detectors 12 provided with hooks 13 at their upper ends for engaging with the warp threads, such detectors being held in the raised position so long as the warp threads are taut and unbroken. The usual means for carrying the detectors are em-

ployed but instead of being stationary as in the old type of loom they are secured to the pivoted levers s so that the complete warp stop motion reciprocates with said levers. When one of the detectors drops by reason of a slack or broken warp thread it descends behind the free end of a bar or arm 14 pivoted at g and coupled by means of a rod 16 to any ordinary type of loom stop mechanism, the arm or bar being moved forward by the detector as will be well understood to stop the loom.

The following are a few of the advantages of the arrangement described:—lightness combined with strength; perfect balance of mechanism and working stresses; strain on yarn reduced to a minimum; no mechanical parts operating in the path of the shuttle; the recess in shuttle race for small-wares need only be the width of the tape or yarn woven and less shedding, height and travel required than in ordinary looms.

It should also be said that the length and position of the suspending or supporting levers can be so arranged as to gradually ease the tension as the healds are lifted and so minimize the strain on the warp threads, and gradually tighten the yarn as the cloth approaches the reed to beat up thus producing clean and regular selvages.

What I claim as my invention and desire to secure by Letters Patent is:—

1. In a loom in which the weft is beaten up against a fixed reed, the combination with such reed, of a warp and cloth supporting frame adapted to be reciprocated in the arc of a circle to enable the weft to be beaten up, said frame having component parts so coupled together that an equal tension on the warp is present throughout the full stroke of the frame.

2. In a loom in which the weft is beaten up against a fixed reed, the combination of such fixed reed, a reciprocating frame, heald frames carried by the reciprocating frame, and connecting rod and crank mechanism directly connected to and reciprocating the healds to accomplish the shedding of the warp.

3. In a loom in which the weft is beaten up against a fixed reed, the combination with such fixed reed and the reciprocating warp and cloth-carrying frame, of means for counter balancing said frame.

4. In a loom in which the weft is beaten up against a fixed reed, the combination with such fixed reed, of an articulated warp carrying frame the component parts of which are so coupled together that an equal tension on the warp is present throughout the full stroke of the frame.

5. In a loom in which the weft is beaten up against a fixed reed, the combination

with said fixed reed, of a reciprocating warp-supporting frame, pivoted balancing levers for supporting the frame, and a take-up motion and rollers carried by and adapted to be operated through the motion of the pivoted levers so as to take up the cloth and also to assist in balancing the mechanism.

6. In a loom having a reciprocating warp frame, pivoted balancing levers for supporting the frame and a warp stop motion car-

ried by the rear set of pivoted levers co-acting with any ordinary means connected with the driving shaft of the loom.

In testimony whereof I have hereunto set my hand in the presence of two witnesses.

THOMAS TROUGHTON JACKSON.
